UNITED STATES PATENT OFFICE.

JAMES ALFORD HOUSE AND CHARLES H. DIMOND, OF BRIDGEPORT, CONN.

DEVICE FOR CLAMPING PATTERNS ON GOODS.

SPECIFICATION forming part of Letters Patent No. 298,470, dated May 13, 1884.

Application filed February 6, 1884. (No model.)

To all whom it may concern:

Be it known that we, JAMES ALFORD HOUSE and CHARLES H. DIMOND, citizens of the United States, residing at Bridgeport, in the 5 county of Fairfield and State of Connecticut, have invented certain new and useful Improvements in Devices for Clamping Patterns to Goods; and we do hereby declare the following to be a full, clear, and exact description of the invention, such as will enable others 10 skilled in the art to which it appertains to make and use the same.

Our invention relates to certain novel and useful improvements in devices for clamping and securing patterns onto goods, and has for 15 its object to operate the clamping-bar by the direct manipulation of the latter, thereby doing away with independent levers and other similar means for accomplishing this purpose, 20 and, furthermore, to do away with a presser-foot, and also to provide such a clamping device as shall have a universal and ready adjustment, while at the same time it is simple and economical in construction; and with these 25 ends in view our invention consists in the details of construction and combination of elements hereinafter fully and in detail explained, and then specifically designated by the claims.

In order that those skilled in the art to which 30 our invention appertains may more fully understand the same, we will proceed to describe its construction and operation, referring by letter to the accompanying drawings, forming a part of this specification, in which—

35 Figure 1 is a perspective showing a pattern clamped onto goods by our improvement, and Fig. 2 a central vertical longitudinal section.

Similar letters denote like parts in both 40 figures of the drawings.

A is a hollow rod having an inwardly-projecting flange or shoulder, B.

C is a coil-spring resting on said flange, and immediately on this spring is a nut, D. This 45 nut is adapted to slide freely within the rod, and is provided with ratchet-teeth E, which extend laterally within an elongated slot, F, in said rod for the purpose presently explained, so that it will be readily understood that when 50 said nut is depressed the action of the spring will tend to throw it back to its normal position.

G is the clamping-bar, threaded at its upper extremity and extended within the rod from the bottom thereof, so as to engage with the 55 nut D. By running the bar up within the nut the former is raised from the pattern, and vice versa.

H is an ordinary spring-pawl pivoted to a collet, I, secured on the rod, and whose normal position is in engagement with the ratchet-teeth in the nut.

Instead of turning the bar around until the action of its thread within the nut brings the lower extremity of said bar against the pattern, 65 we are enabled to accomplish the same result in less time by simply pulling the bar down, thereby depressing the nut against the spring. The pawl H will engage with the ratchet-teeth on the nut and prevent the bar from flying 70 back after it has been brought down. When it is desired to remove the pattern from the goods, the bar may either be run back within the nut, or the heel end of the pawl may be depressed and the latter thrown out of engagement with the ratchet-teeth, and thereby cause the spring to act against the nut and throw the bar up. The rod is pivoted at its upper extremity to a block or frame, J, arranged to travel on any suitable track, K, the relation between 75 said block and rod being such that the latter is permitted to swing freely in a direction transverse to the movement of the block for the obvious purpose of bringing the clamping-bar into operation at any point of the cutting-table.

The operation of our improvement is as follows: The pattern is placed upon the goods, the latter being arranged in as many thicknesses as desired for the purpose of cutting 90 duplicate patterns. The clamping-bar is now brought into the required position over the pattern and brought down firmly upon the latter, as hereinbefore set forth. If the lower extremity of the bar is considerably above the 95 level of the pattern, (as frequently happens whenever the bar, having been raised to accommodate many thicknesses of goods, has been left in that position,) instead of running the bar down onto the pattern we simply pull it out and give it several turns; but if the lower extremity of the bar is close to the pattern, then it may not be desirable to pull the bar down, 100 and it is therefore given a few turns, and there-

by brought firmly against the pattern. The bar will be held against upward movement when the pattern is clamped by the pawl or by the abutment of the nut against the upper 5 wall of the slot F. The clamping-bar is bowed for convenience, in order that the operator may swing it around to manipulate the cutting-knife more readily.

We do not wish to confine ourselves to the 10 exact method shown of pivoting the rod to the traveling block, as a ball-and-socket joint may be used, or any other similar and suitable means employed in this connection.

What we claim as new, and desire to secure 15 by Letters Patent, is—

1. A device for clamping patterns onto goods, consisting of a rod adapted to be adjusted to any vertical plane, and having interiorly-arranged therein a threaded clamping-bar en- 20 gaging with a nut within said rod, substan- tially as set forth.

2. A device for clamping patterns to goods, consisting of a rod pivotally attached to a traveling block or frame, and having interiorly ar- 25 ranged therein a threaded clamping-bar adapt- ed to travel in a nut, substantially as described.

3. In a device for clamping patterns to goods, a rod pivotally attached to a traveling block or frame, and having interiorly arranged there- 30 in a nut provided with ratchet-teeth and sup- ported in an elevated position by a spring, in combination with a threaded clamping-bar

adapted to travel in said nut, and a pawl at- 35 tached to said rod and adapted to engage with said teeth and hold the bar against upward movement, substantially as shown and de- scribed.

4. In a device for clamping patterns to goods, the threaded clamping-bar adapted to engage with an adjustable nut arranged interior of a 40 rod capable of being adjusted to any vertical plane, substantially as set forth and described.

5. The threaded clamping-bar adapted to engage with a nut in the rod, in combination with means independent of the screw action 45 of the bar for enabling the latter to be brought down and held upon the pattern, and return- ing said bar to its normal position, substan- tially as specified.

6. The rod A, having shoulder B and elon- 50 gated slot F, and with nut D and coil-spring C, arranged interiorly therein, in combination with the threaded clamping-bar G, sliding block J, and pawl H, attached to said rod and engaging with teeth in said pawl, substantially as and for the purpose set forth.

In testimony whereof we affix our signatures in presence of two witnesses.

JAMES ALFORD HOUSE.
CHARLES H. DIMOND.
